UNITED STATES PATENT OFFICE.

FRANK E. HEALEY, OF MORRISVILLE, VERMONT.

BOOK-SUPPORT.

SPECIFICATION forming part of Letters Patent No. 396,741, dated January 29, 1889.

Application filed April 5, 1888. Serial No. 269,747. (No model.)

To all whom it may concern:

Be it known that I, FRANK E. HEALEY, of Morrisville, in the county of Lamoille and State of Vermont, have invented certain new and useful Improvements in Book-Supports: and I do hereby declare the following to be a full, clear, and exact description of the same, reference being had to the accompanying drawings; forming a part of this specification, to and to the figures and letters of reference marked thereon.

My invention relates particularly to improvements in desks designed for use in churches, counting-houses, and elsewhere where large books are required to be supported and handled; and it has for its object to provide a desk so constructed that it will properly support and maintain in horizontal position both portions of a book when laid upon it and opened, and will so adapt itself to the varying bulk of the different portions of said book as to rise automatically under the lighter portion and descend automatically under that portion which is heavier and thus not only present both exposed pages of the book in a substantially horizontal position most convenient for inspection, but also prevent straining of and injury to the cover of the book.

It has, further, for its object to provide means for regulating the extent of movement of the rising and falling supports of the desk, for bringing said supports to a state of equilibrium after use, and for locking said supports at any particular point of adjustment when desired, all as will be hereinafter fully described.

Referring to the accompanying drawings, Figure 1 represents a perspective view of a desk constructed in accordance with my invention. Fig. 2 is a longitudinal sectional view of the same. Fig. 3 is a perspective view showing the devices upon which the movable supports of the desk are carried, and by which the simultaneous movements of the same are effected. Fig. 4 is a detailed view of the devices for limiting the extent of movement of the vertically-movable supports of the desk to correspond to the thickness of the book to be supported. Fig. 5 is a detail view showing how one part of the desk may be utilized to support a ledger or other book of

account, while the other serves as a rest for the arm in making entries in said book.

Similar letters of reference in the several figures indicate the same parts.

My desk consists, essentially, of a box or casing, A, two vertically-movable supports, B B', and connecting mechanism arranged beneath said movable supports for causing one of said movable supports to be automatically raised when the other of said supports is depressed. Said connecting mechanism is composed, preferably, of two curved or angular levers, C, pivoted centrally at D and having connecting-bars C' near their ends and four arms or levers, E, pivoted at their lower ends, as shown at F, and provided at or near their middles with laterally-projecting pins or studs G, which enter longitudinal slots H in the centrally-pivoted levers C, as shown in Fig. 3.

The extremities of the levers C and the upper ends of the arms or levers E are preferably provided with friction-rollers I, and upon these friction-rollers the two vertically-movable supports B B' rest, as shown in Fig. 2.

It will be seen that the arrangement of the parts is such that when the support B, for instance, is forced down, the ends of the levers C and the co-operating arms or levers E beneath it will be depressed, while the opposite end of said lever C and its corresponding pair of arms or levers E will be elevated, thus lifting or raising the support B' a corresponding degree.

The practical operation of the invention is as follows: When a book is placed upon the support B, for instance, said support will descend, while support B' will rise; but if the book is opened, so as to rest partly upon one support and partly upon the other, the said supports will adjust themselves in accordance with the distribution of weight—that is to say, if the heavier part of the book after the latter is opened continues to rest upon support B, that support will remain down, while support B' will remain elevated; but if the opening of the book transfers the greater weight to the support B', that support will descend and the other one will rise. Should the weight of the book happen to be distributed equally between the two supports, they would be brought to a state of equilibrium and stand at the same level, as will be

readily understood. By this arrangement of self-adjusting supports for the book both covers of the book are properly supported and the exposed page on each support is presented in a substantially horizontal plane, while all wrenching and improper bending of the back is avoided. In point of fact, the said automatically-acting supports deal with the book just as any careful reader of it would—that is to say, they support both covers at all times and do not permit it to be opened too wide, so as to impair the binding.

In order that no injury may be done to the back of the book through abrasion, I preferably concave the corners *b* of the supports *B* *B'*, as shown in Fig. 1.

As it is desirable that both supports *B* *B'* should normally stand level, I by preference apply to each of the cross-pieces *C'* of the levers *C* a light spring, *s*. These springs, while not strong enough to interfere with the prompt action of the supports when a book is placed upon them, serve well to bring back said supports to a common level after the book or other object has been removed from them.

The throw or extent of movement of the supports *B* *B'* may be regulated by means of set-screws *T*, or their equivalents, applied to the cross-bars *C'* and adapted to impinge upon the bottom of the box or case *A*. This provision is desirable, since it enables the extent of movement of the supports to be fixed with reference to the thickness of the book designed to be used upon the desk. Without it the weight of one portion of a comparatively thin book would cause such a descent of one of the supports as to carry the cover bearing the lighter portion of said book far above a horizontal plane, and thus defeat one of the objects of the invention.

To enable the supports to be locked and secured in any desired position of adjustment, I provide a set-screw, *U*, adapted to work through the box or case *A* and impinge upon one of the supports *B* *B'*, or engage with a perforated strip of brass or other metal, *V*, or a rubber strip applied to said support, as shown in Fig. 1. This locking means may be applied to either one or both of the supports, as desired.

In Fig. 5 I have shown the desk as arranged to give support to the hand and arm while writing in a ledger or other large account-book. In this instance the left-hand support is made wider than the one at the right and a supplemental adjustable support, *W*, is provided for the empty cover of the book. By placing the ledger on this wider left-hand support and adjusting the said supports to the proper levels and securing them at said point of adjustment by the described locking means great convenience in making entries in the book will result.

Small apertures *O* will be noticed in the several figures. These are for the purpose of permitting the free escape of air, which might

otherwise become confined in the case and operate disadvantageously when the supports *B* *B'* are shifted.

Having thus described my invention, what I claim as new is—

1. In a book-support, the combination, with the base, the movable supports, and the bent levers pivoted at the center to the base and supporting one side of the movable supports, of co-operating arms or levers pivoted at one end on the base, supported at an intermediate point upon the bent levers, and serving to support the other side of the movable supports, substantially as described. 70 75 80

2. The combination, with the box or casting, the movable supports, and the centrally-pivoted levers provided with slots and serving to support one side of the movable supports, of the co-operating pivoted levers or arms supporting the other side of the movable supports, being themselves supported by pins or studs entering said slots in the centrally-pivoted levers, substantially as de- 90 95 100

3. The combination, with the movable supports and the centrally-pivoted levers supporting one side of the movable supports, of the co-operating pivoted levers or arms sup- 95 100

ported by the centrally-pivoted levers for supporting the opposite side of the movable supports, and the springs for returning both the centrally-pivoted levers and the co-operating levers or arms to normal position, substan- 100 105 110

tially as described.

4. In a book-support, the combination, with the centrally-pivoted levers carrying the movable supports free to be moved in either direction by the weight of the book, of the co-operating pivoted levers or arms supported by the centrally-pivoted levers, and the adjustable stops for limiting the extent of movement in either direction, substantially as described. 110 115 120

5. In a book-support, the combination, with

the levers pivoted at the center and a sup-

port carried by each end of the levers, each

adapted to be moved down by the weight of

the book and cause a corresponding elevation

of the opposite support, of adjustable stops

for limiting the extent of movement in either

direction, whereby the support may be ad-

justed to accommodate books of different

thicknesses, substantially as described. 120 125

6. The combination, with the movable sup-

ports, the centrally-pivoted levers supporting

one side thereof, and the pivoted levers or

arms supported by the centrally-pivoted le-

vers supporting the other side, of the springs

for returning the parts to normal position

when moved in either direction, and adjust-

able stops for limiting the extent of such

movement, substantially as described. 125 130

7. The combination, with two supports free

to move in either direction and connecting

mechanism by which one support is raised

when the other is depressed, of springs for

bringing said supports to equilibrium when

the moving force is removed, and adjustable stops for limiting the downward movement of said supports, substantially as described.

8. In a book-support, the combination, with
5 the casing, the movable supports in the same, and connecting mechanism by which one is raised when the other is depressed, of a lock for rigidly connecting the casing and one of

the supports at any desired point of adjustment, but allowing the supports free movement when disengaged, substantially as described.
